(57) **CLAIM**

The ornamental design for an outer surface of a baker, as shown and described.

DESCRIPTION

FIG. 1 is a perspective view of an outer surface of a baker according to the new design;

FIG. 2 is a side elevation view of one side of the outer surface of the baker shown in FIG. 1, the other side being identical;

FIG. 3 is a front view of the outer surface of the baker shown in FIG. 1, the rear view being identical;

FIG. 4 is a top view of the outer surface of the baker shown in FIG. 1; and,

FIG. 5 is a bottom view of the outer surface of the baker shown in FIG. 1.

Features shown in broken lines in the drawings are not part of the claim.
